(57) CLAIM

The ornamental design for a dual container assembly, as shown and described.

DESCRIPTION

FIG. 1 is a perspective view of the dual container assembly taken from above, the front and the right side thereof; FIG. 2 is a front elevational view of the dual container assembly;

FIG. 3 is a rear elevational view of the dual container assembly;

FIG. 4 is a left side elevational view of the dual container assembly;

FIG. 5 is a right side elevational view of the dual container assembly;

FIG. 6 is a top plan view of the dual container assembly; and, FIG. 7 is a bottom plan view of the dual container assembly. The left and right cylindrical portions of the dual container assembly have open bottoms, and each is intended to house a compressible bag.
